Specification of Letters Patent. Patented Mar. 23, 1920.

Original applications filed May 13, 1916, Serial Nos. 97,388 and 97,389. Divided and this application filed June 4, 1918. Serial No. 238,194.

To all whom it may concern:

Be it known that I, FREDERICK W. S. STOKES, a subject of the King of England, and residing at 32 Victoria street, Westminster, London, S. W., England, have invented certain new and useful Improvements in Ordnance, of which the following is a specification.

This invention relates to ordnance, more particularly to guns of the howitzer type, such as trench mortars, and to a projectile and cartridge peculiarly adapted to coöperate with the gun so that the gun will be self-clearing, each cartridge case being carried off with its projectile. The gun, therefore, requires no breeching mechanism and may be operated with great rapidity.

This application is a division of my pending applications, Serial Numbers 97,388 and 97,389, filed May 13, 1916. In the first mentioned application I have fully described and illustrated a gun embodying the principles of the present invention, and in the second application there is described and illustrated a projectile adapted to coöperate with the gun. In the present application the peculiar relation and co-operation of the gun, projectile and cartridge, whereby the gun is self-clearing and adapted for rapid operation, is particularly described and claimed.

In the accompanying drawings which form a part of this application:

Figure 1 is a side elevation of the improved gun and support set up ready for use;

Fig. 2 is a front elevation of the same;

Fig. 3 is a longitudinal sectional elevation of the gun partly broken away and on an enlarged scale;

Fig. 4 is a sectional view of one form of projectile adapted for use in the improved gun;

Fig. 5 is a bottom plan view of the projectile shown in Fig. 4; and

Fig. 6 is a sectional view of the lower or closed end of the gun and a projectile, such as shown in Fig. 4, in the position in which it is located at the instant of firing, the cartridge within the projectile and the plug or block which supports the cartridge at the moment of firing being shown in side elevation.

Referring to Figs. 1, 2 and 3 the gun comprises a barrel A conveniently formed of a solid drawn steel tube having its rear end reduced in some convenient manner as at A', the reduced portion being externally screw-threaded. On to this reduced end is screwed a cap B provided with a spherical or otherwise suitably shaped head B' and having formed or mounted on it a cylindrical plug or block C so that this plug projects through the reduced end A' of the barrel into the breech chamber A². The end of the block C is flat or slightly convex and carries centrally disposed therein a small pointed projection C' which constitutes a striker. At a suitable point in the length of the barrel A is a hole through which projects into the bore a pin D which is so carried by a sleeve E that it can slide freely therein and constitute a removable catch adapted to hold the projectile when inserted in the muzzle. Pivoted at D' to the outer end of the pin D is a two-armed lever one arm F of which is so formed as to permit of having attached thereto a cord or the like, while the other arm F' is so disposed and shaped that when the lever is turned about its pivot D' the part F' will bear against the end of the sleeve E and retain the pin D in its withdrawn position so that its inner end does not project into the bore of the gun. The inner end of the pin D is conveniently formed slightly larger than the outer end so that, by abutting against a shoulder formed within the sleeve E, the complete withdrawal of the pin D is prevented.

A metal plate G of suitable dimensions, flanged or otherwise shaped as to its underside so as to obtain a hold on the ground, has formed in it a series of depressions G' each adapted to receive the head B' of the breech cap B.

To the fore end of the gun is attached a support in the form of legs whose length can be varied. A convenient construction of these legs is shown in Figs. 1 and 2. A collar H fixed in some suitable manner around the fore end of the gun is provided with two lugs H' to each of which is pivoted a suitable length of rod J whose end is threaded with a left hand screw-thread. Another length of rod J' has one end similarly threaded but with a right hand thread

and the two ends of these rods J and J' engage the correspondingly screw-threaded ends of a turn buckle J². Loosely mounted on the other end of the rod J' is a plate J³ flanged as at J⁴ or otherwise formed on its underside so as to take a hold on the ground.

The gun is set up in the manner shown in Figs. 1 and 2 with the plate G embedded in the ground and the breech of the gun resting thereon with the head B' of the breech cap engaging one of the depressions G'. The fore end of the gun barrel A is supported by the legs J J' the plates J³ on the end of which are embedded in the ground. The gun can now be trained in the required direction traversing being effected by moving the breech to one side or the other so that the end engages a depression G' in the plate G. The desired elevation is attained by rotating the turn buckle J² and so varying the length of the legs supporting the fore end. Suitable adjustment of the length of these legs also has a traversing effect. It will be noted that the gun is set up with the barrel forming a considerable angle to the horizontal. The pin D is now pushed in so that its end projects into the bore of the gun and a projectile K is inserted in the muzzle being retained there by the base of the projectile resting on the pin D. This projectile carries at its rear end a cartridge provided with a percussion cap and the projectile itself is of such dimensions with relation to the bore of the gun that a certain amount of windage is allowed in order to permit the projectile to slide freely down the bore. When the gun is to be fired the pin D is withdrawn by pulling the cord attached to the lever F, the pull being maintained until the projectile has left the gun. As soon as the pin D is withdrawn the projectile slides down the bore of the gun into the breech and detonates the cartridge on the striker C'.

In some cases the catch or the like above described as being disposed in the barrel of the gun for the purpose of holding the projectile until it is to be fired, may be entirely dispensed with or some equivalent device combined with the projectile. Thus for instance for quick firing of the gun the projectile may be held in the hand in the muzzle until it is desired to fire the gun when the projectile is released and allowed to fall into the breech. Yet again, by drilling a small hole at a suitable point in the wall of the projectile and inserting a pin therein, the projectile will be retained in the muzzle of the gun as by the above described catch.

When the pin is withdrawn by pulling a cord or otherwise, the projectile is released and will fall into the breech and be discharged.

Owing to the manner in which the striker C' is mounted on the block C which pro-

jects into the breech chamber A² there is provided around the striker a space in which the gases resulting from the explosion of the propellant charge can expand sufficiently to reduce the maximum bursting pressure on the walls of the gun while, however, allowing them to develop the necessary propellant force. The dimensions of this space for the expansion of the gases is further increased by reason of the cartridge carrying the propellant charge being of less diameter than the projectile and carried in a chamber formed or mounted on the rear end of the projectile. The position of the projectile at the moment of discharge after it has descended into the breech of the gun is indicated in dotted lines in Fig. 1 the expansion space in the breech chamber A² being also indicated around the cartridge chamber K' on the rear of the projectile and the striker block C. A hole B² is conveniently formed in the head of the breech cap B through which a pin can be passed for the purpose of enabling the breech cap to be unscrewed. This permits access to the breech chamber A² and also allows the striker block C and the position of the striker C' to be adjusted. The striker block C is conveniently of the same diameter as the head of the cartridge containing the propellant charge and it may be noted that though this striker block is removable and adjustable in the manner described yet in effect this block together with the cap constitute a fixed breech block for the gun inasmuch as the gun is loaded through the muzzle.

The laying of the gun as to its elevation is facilitated by providing a device such as shown in Fig. 1. This comprises a quadrantal plate M mounted in some suitable manner on the upper side of the barrel so as to project radially from the axis thereof. Pivoted to this plate is a lever M' which carries a spirit level and has its free end forked so that a portion of the lever lies on either side of the quadrant portion of the plate M. This quadrant is graduated on one side with a scale of range distances and on the other side is provided with a time scale corresponding to these distances. When the gun is to be trained the lever M' is raised until its end cuts the scale at the point corresponding to the distance to which it is desired the projectile should be thrown or at the figure corresponding to the desired time of flight. The elevation of the gun is now varied until the lever M' is level.

In order to permit of a periscope being mounted on the gun there is formed in the base of the quadrantal plate M a hole or socket M² into which can be inserted a rod or pin pivotally mounted on the lower end of the periscope. In this way the periscope can be readily and truly fixed in position

and is then available for use in training the gun.

Figs. 4 and 5 illustrate one form of projectile especially adapted for use in the gun above described. Referring to these figures, K describes a hollow cylindrical shell body having an integral solid base K' and a tapering head K² having a central opening in the head adapted to be closed by a plug K³. 10 The shell may be charged with a suitable explosive through the opening and securely closed by means of a plug or other suitable device. Any suitable device may be employed for firing the explosive charge. As 15 shown in the drawings there is formed in the base K' an annular recess K⁴ from which a passage K⁵ leads into the interior of the shell. In the recess K⁴ is placed a length of fuse K⁶ with one end at the passage K⁵ so 20 that there is formed an annulus of fuse material which when ignited at any point in the circle will burn at a known rate and in due course either ignite a detonator disposed in the shell or directly explode the 25 charge within the shell. The annulus of fuse material is covered by a rotatable time disk O which is held in place by the tubular cartridge holder P, the forward end of which is reduced and threaded into the base 30 as at P². The threaded extension of the cartridge holder passes through a central opening in the disk O and will secure the disk in any desired position. The hole O' in the disk registers with the groove K⁴ and 35 admits flame to ignite the fuse when the projectile is fired. The periphery of the disk may be graduated so that it can be rotated to set the hole O' in any desired relation to the opening K⁵. The time between 40 the firing and the explosion of the projectile may be thus determined. The hole O' may be provided with a removable cover which is adapted to be torn away or perforated when the shell is about to be used. 45 The tubular cartridge chamber P is provided with lateral openings P' to permit the explosion gases from the cartridge R to escape into the space within the gun in rear of the projectile and expand therein. The 50 cartridge R is similar in appearance to a shot gun cartridge being provided with a central primer or cap R' adapted to be detonated by firing pin C' on plug C. It will be understood that many forms of projectile may be adapted to be fired by the means 55 and from the gun herein described, and that the projectile shown in Figs. 4, 5 and 6 is simply adopted for purposes of illustration.

The operation of the gun is illustrated in 60 Fig. 6. This figure is an enlargement of a part of Fig. 2 in section showing a projectile in the breech end of the gun and in the position it occupies at the instant of firing. The invention is particularly applicable to 65 smooth bore guns and the projectiles are

made with a slight clearance so that they will readily slide through the barrel of the gun when inserted at the muzzle.

The cylindrical block C preferably projects into the gun and is of substantially the diameter of the cartridge R, or slightly larger. At the instant of impact the firing pin or point C' strikes and detonates the primer R' exploding the charge in the cartridge. At this instant the cartridge is supported by 75 the block C and its head cannot blow off. The gases are blown out through the openings P' in the cartridge chamber, and the pressure within the cartridge case causes it to be gripped tightly by the cartridge chamber. The gases expand in the breech chamber O² and force the projectile out of the gun, the projectile carrying the cartridge case with it and leaving the gun free for the insertion of the next projectile. As there is 80 no breech to open and close and the gun is self-clearing, it may be fired very rapidly. In some cases the movable support D may be dispensed with and the projectiles dropped directly into the gun which facilitates rapidity in firing. 85

It will be noted that there is a peculiar interdependence in functioning between the projectile, the cartridge, and the gun. The support or block C prevents the head from 90 being blown off the cartridge and sustains the cartridge in position within the cartridge chamber while the gases generated within it are blown through the lateral openings into the breech chamber O². The 95 cartridge also cooperates with the cartridge chamber in that its lateral walls are blown through openings P' and more or less engage with these openings, the cartridge case being thus prevented from blowing backward and being engaged laterally with the cartridge chamber is carried off with the projectile. This is very important as it leaves the gun substantially clean at all 100 times and permits of projectiles being inserted in the muzzle of the gun as rapidly as they can be handled. When a projectile is dropped into the gun it slides rapidly to the breech end and is instantly projected from the muzzle. 105

Having thus described the invention what is claimed as new and desired to be secured by Letters Patent is:

1. In combination with a gun having a firing pin, a projectile having a chamber at its rear end adapted to receive a cartridge to be fired by said firing pin, said cartridge chamber having lateral openings for the escape of gases into the breech of the gun in rear of the projectile. 120

2. In combination with a gun having a firing pin and a support for a cartridge surrounding the firing pin, a projectile having at its rear end a cartridge chamber, and a cartridge adapted to said chamber and 130

having a primer arranged to contact with the firing pin when the projectile is dropped into the gun.

3. In combination with a muzzle-loading smooth-bore gun having a firing pin at its breech end, a projectile having a cartridge chamber at its rear end adapted to hold the cartridge with its primer in position to contact with the firing pin when the projectile is dropped into the gun.

4. In combination with a smooth-bore muzzle-loading gun having a block centrally arranged at its breech end adapted to support the head of a cartridge, and a firing pin on said block adapted to detonate the cartridge, a projectile having at its base an axial cartridge chamber to receive a cartridge, said chamber having lateral openings for the escape of gases.

5. In combination with a smooth-bore muzzle-loading gun having a block centrally arranged at its breech end adapted to support the head of a cartridge, and a firing pin on said block adapted to detonate the cartridge, a projectile having at its base an axial cartridge chamber to receive a cartridge, said chamber having lateral openings for the escape of gases, and a cartridge adapted to said chamber having a detonator arranged to contact with the firing pin.

6. In combination with a smooth-bore muzzle-loading gun having a closed breech, a firing pin axially arranged in the breech and a support for a cartridge surrounding the firing pin, a projectile having at its rear end a tubular cartridge chamber of substan-

tially less diameter than the projectile, said chamber having lateral openings for the escape of gases, and a cartridge in said chamber adapted to be detonated by the firing pin, the support surrounding the firing pin being arranged to prevent the cartridge case from blowing rearward out of its chamber, whereby the cartridge case is carried off by the projectile.

7. In combination with a smooth-bore muzzle-loading gun having a centrally arranged firing pin and support for a cartridge, a projectile having a centrally arranged cartridge chamber at its rear end provided with lateral openings, a cartridge in said chamber adapted to discharge its explosion gases through said openings, and a fuse in the base of the projectile adjacent the cartridge chamber adapted to be ignited by the flame issuing from said lateral openings.

8. The combination with a smooth-bore muzzle-loading gun having an inwardly projecting cylindrical block at its rear end adapted to support the end of a cartridge and having a firing pin, of a projectile having a cartridge chamber projecting rearwardly from its base in line with said cylindrical block, said cartridge chamber having lateral openings and a cartridge in said chamber adapted to be simultaneously fired by said pin and supported by said block, for the purpose set forth.

In testimony whereof I affix my signature.

FREDERICK WILFRID SCOTT STOKES.
